UNITED STATES PATENT OFFICE.

CHESTER A. MACOMIC, OF CHICAGO, ILLINOIS.

TYPE HOLDER.

Application filed December 27, 1921. Serial No. 525,173.

To all whom it may concern:

Be it known that I, CHESTER A. MACOMIC, a citizen of the United States of America, and a resident of Chicago, county of Cook 5 and State of Illinois, have invented a new and useful Improvement in Type Holders, of which the following is a specification.

This invention relates to type holders intended for retaining in alined position a 10 line of type, while the type are being transferred from a typesetting machine to printing or casting means, and for supporting the type while in the printing mechanism. The typesetting machine for which the present 15 holder is particularly designed is the one described in the patent to Chester A. Macomic, typesetting machine, No. 1,301,146, issued April 22, 1919, and in the application for patent of Bester R. Webster, executed on October 4, 1921, and filed of even date here- 20 with.

The objects of the invention are to provide improved means for supporting, alining, and locking in set position a line of selected type.

25 The objects of the invention are accomplished by the device shown in the accompanying drawings, wherein—

Figure 1 is a perspective view of the type holder showing a few type supported there- 30 in.

Fig. 2 is a view in side elevation of the type supporting bar.

Fig. 3 is a side elevation of the type locking bar, which is slidably mounted within 35 the type supporting bar.

Fig. 4 is an enlarged longitudinal sectional view of the type holder.

Figs. 5 and 6 are end views thereof.

Fig. 7 is a transverse sectional detail taken 40 on the line 7—7 of Fig. 4.

Fig. 8 is a transverse sectional detail taken on the line 8—8 of Fig. 4.

Fig. 9 is a perspective view of a type suitably formed for coaction with the type 45 holder.

The machine described in the above-mentioned patent to Macomic, and for which this type holder is designed, consists of a key-operated typewriter having provision for 50 operating type selecting mechanism, which is adapted to successively coat with type supporting plates of a type magazine for the purpose of successively filling type holders of the type to which this application for patent is directed. After a plurality of such

type holders are filled with the desired type, they are simultaneously operated upon to lock the type in set position, and then are removed from the machine, without changing their order, to a printing mechanism or 60 matrix making machine.

The type holder consists of a transversely slotted bar, the slots of which are adapted to register with similar type supporting slots in the type plates of the type magazine. The type supporting bar is longitudinally grooved to receive a comb-shaped locking and alining bar. This locking bar is shiftable for a slight distance along the groove in the supporting bar so that the 65 teeth of the locking bar may be engaged with or disengaged from the type. The type supporting bar and the locking bar may be machined from solid stock, or drawn and milled or punched and formed from flat 70 stock.

As finished, the supporting bar 1 is milled to provide the head portions 2 and 3, and a plurality of upwardly projecting spacing teeth 4. A rectangular groove 5 in the 80 bottom of the bar, and extending upwardly into the teeth 4 thereof, extends from end to end of bar 1 and receives the locking and alining bar 6, which is provided with a plurality of upwardly projecting T-shaped 85 teeth 7. The locking bar 6 is slightly movable along the groove in bar 1, and is normally urged into locking position to the right as illustrated in Fig. 4, by a coiled spring 8. This spring bears between the 90 end of the locking bar and a plug 9 in the end of bar 1. The movement of the locking bar 6 under the action of the spring, is limited by the shoulders 10 and 11. The type 12 as shown in Fig. 5, are provided 95 with T-shaped recesses 13 on one side, which are entered by the teeth of the locking bar when it is permitted to move to the right under the action of its spring 8. In its normal position, the locking bar is shifted to the left (Fig. 4) against the action of the spring 8 so that its teeth are hidden within the teeth 4 of bar 1. The movement of the locking bar 6 to releasing position to the left, Fig. 4, is limited by a shoulder 14 in a 100 small block 15, seated in the groove 5 and riveted to the head 2. A similar block 15 is riveted to head 3 and is provided with the limiting shoulder 11. The teeth 4 of the supporting bar are slightly beveled at their 105 110

front and rear edges so as to easily permit type to pass into and through the slots of the bar.

When in operation the locking bars 6 are held in the left hand position, Fig. 4, where the teeth thereof are hidden in the slots in the teeth 4 of the supporting bar. The slots are therefore open to receive type. When the holder is filled as desired, the locking bar is released, spring 8 urging it to the right, as shown in Fig. 4, with its teeth 7 bearing against the type within the T-shaped recesses 13 in the sides thereof.

Although but one specific embodiment of this invention has been herein shown and described, it will be understood that numerous details of the construction shown may be altered or omitted without departing from the spirit of this invention as defined by the following claims.

I claim:

1. A type holder, comprising a comb-shaped bar having a longitudinal groove, a type locking member slideable in said groove, said locking member having teeth for engaging type.

2. A type holder, comprising a comb-shaped bar having a longitudinal groove, a type locking member slideable in said groove, said locking member having teeth for engaging type, and type in the comb-shaped bar having recesses for receiving the teeth of said locking bar.

3. A type holder, comprising a comb-shaped bar having a longitudinal groove, a type locking member slideable in said groove, said locking member having teeth for engaging type, and a spring mounted in said comb-shaped bar and engaging said locking member.

4. A type holder, comprising a comb-shaped bar having a longitudinal groove, a type locking member slideable in said groove, said locking member having teeth for engaging type, type in the comb-shaped bar having recesses for receiving the teeth of said locking bar, and means for normally urging said locking bar into locking engagement with the type.

Signed at Chicago this 23rd day of December 1921.

CHESTER A. MACOMIC.
